UNITED STATES PATENT OFFICE.

THURE E. FLOOD, OF CHICAGO, ILLINOIS.

CARTON.

Application filed April 18, 1922. Serial No. 554,657.

To all whom it may concern:

Be it known that I, THURE E. FLOOD, a citizen of the United States, residing at Chicago, in the county of Cook and State 5 of Illinois, have invented new and useful Improvements in Cartons, of which the following is a specification.

This invention relates to a carton particularly designed for retaining a plurality of smaller cartons either for shipment or storage, and an object of the invention is to provide a carton of this type, which may be constructed wholly of pasteboard or analogous material and is designed to 15 replace the tin or metal and glass boxes employed for retaining packages or loose cakes, crackers or the like.

The metal boxes or cases used for containing cakes, crackers or the like both for 20 shipping and while stored on the shelves of the retailer are quite an item in the expense of the marketing of this type of goods and usually the retailer is required to make a cash deposit for every case he receives 25 preventing his obtaining the use of such money, and it is an object of this invention to provide a carton which can be constructed at a comparatively low cost and used to retain the cakes, crackers or the 30 like either loose or in boxes, and the cost of which carton will be such that the manufacturer may provide a carton for each lot of the goods eliminating not only the expense occasioned by the metal cases but 35 also eliminating the time and expense absorbed in looking after the metal cases and keeping the account of deposits thereon.

Another object of this invention is to provide a carton as specified which is composed 40 of interlocking sections adapted to provide a relatively rigid carton and which has a door opening at one end thereof through which the contents of the carton may be removed.

45 Other objects of the invention will appear in the following detailed description taken in connection with the accompanying drawings wherein:

Fig. 1 is a perspective view of the improved carton.

50 Fig. 2 is a fragmentary perspective of the carton showing the binder removed.

Figs. 3 and 4 are plan views of the blanks from which the carton is formed.

Fig. 5 is a vertical section through the 55 carton.

Referring more particularly to the drawings, the improved carton 1, which is substantially rectangular in shape is formed of the two blanks 2 and 3 each of which are 60 formed of pasteboard or analogous material. The blank 2 is scored to provide four rectangular panels 4, 5, 6 and 7 which have flaps 8 along their side edges, formed by the scoring of the blank as shown at 9. The end panel 7 has a tab 10 formed across against its outer end, as clearly shown in Fig. 3 of the drawings, while the panel 4, which forms the front end of the carton has a tongue 11 cut therefrom, the outer edge 12 65 of which aligns with the outer edge of the panel 4, as clearly shown in Fig. 3 of the drawings. The panel is cut away as shown at 13 to provide triangular openings at each end of the tongue 11, which triangular openings terminate in inwardly extending substantially rectangular portions which are relatively small and located at the ends of the tongue. The tongue 11 is equal in depth to the width of the flap 10 so that 70 when the box is assembled, and the tongue is folded against the outer surface of the flap 10, in interlocking engagement therewith as shown in Fig. 2 of the drawings, the upper or outer edge of the tongue will be 75 flushed with the top of the box, which top is formed by the end panel or rectangular panel 7.

The blank 2 when folded forms the front 14, bottom 15, rear end 16 and top 7 of the 80 carton, while the sides of the carton and the inner bottom thereof are formed by the blank 3 which is scored transversely as shown at 18 to provide the side forming panels 19 and 20 and the inner bottom forming panel 21 when the carton is assembled, rests upon the upper surface of the bottom 15, as clearly shown in Fig. 5 of the drawings, while the side forming panels 19 and 20 form the sides of the box, the side forming panels 19 and 20 have substantially frusto triangular tongues 23 formed thereon intermediate their ends the outer edges of which are flushed with the outer edges of the respective panels, as clearly shown in Fig. 4 85 of the drawings. The tongues 23 interlock with the tabs 8 formed along the sides of the top forming panel 7 when the carton is 90 95 100 105

assembled, and as will be noted by particular reference to Figs. 2 and 5 of the drawings the respective tongues are bent outwardly so as to engage against the outer surfaces of the tabs 8 and 10 for interlocking the folded or formed blanks 2 and 3. The blank 3 has tabs 24 formed along the ends of its various panels which overlap the adjacent edges or corners of the carton, as clearly shown in Fig. 5 of the drawings, the tabs 8 overlapping the corners adjacent to which they fall or come in the forming of the box, thereby providing a relatively rigid box or carton which is reinforced at its corners and which may be cheaply constructed. The various overlapping tabs are connected by paper fasteners or analogous structures as shown at 25 to securely hold the carton in its formed position.

A binder strip 26 is mounted about the top corner of the carton and is secured thereto by any suitable type of adhesive, the said strip preferably being formed of gummed paper and it serves to securely bind the tongues 11 and 23 against the respective flaps 8 and 10 and also to cooperate in securely holding the carton formed. The front 8 has a door or panel 27 cut therein which may be opened to permit access to the interior of the carton for the purpose of removing the contents therefrom, in comparatively small lots or in single packages thereby particularly adapting the carton for use in delicatessen or grocery stores where comparatively small quantities of cakes, crackers or the like are sold.

The door panel 27 may be sealed when the carton is in shipment, and the seal cut to permit the dispensing of the contents of the carton and by the placing of a facsimile of the contents of the carton on the front 4, the contents of the carton may be illustrated so that purchasers may readily understand the types of cakes, crackers, or the like contained in the carton. The door is sealed when the carton is in shipment or before dispensing of the contents by a paper sealing tape as indicated at 26.

It is, of course, to be understood that the invention may be constructed in other manners and the parts associated in different relations and, therefore, I do not desire to be limited in any manner except as set forth in the claims hereunto appended.

Having thus described my invention what I claim is:

1. A carton formed of two blanks of foldable material, one scored to provide a plurality of rectangular panels for forming the front, bottom, rear and top of the carton and the other blank being scored to provide the sides and inner bottom of the carton, all of said panels having tabs along certain of their edges adapted to be folded at right angles to the respective panels for reinforcing the corners of the carton, tongues formed on the free edge of the front and side forming panels of the carton and adapted to interlock with the tabs on the top forming panels, and a binder about the top of the carton engaging the sides and top thereof.

2. A carton formed of two blanks of foldable material, one scored to provide a plurality of rectangular panels for forming the front, bottom, rear and top of the carton and the other blank being scored to provide the sides and inner bottom of the carton, all of said panels having tabs along certain of their edges adapted to be folded at right angles to the respective panels for reinforcing the corners of the carton, tongues formed on the free edge of the front and side forming panels of the carton and adapted to interlock with the tabs on the top forming panels, said front side having a door panel cut therefrom and adapted to be swung outwardly to permit access to the interior of the carton.

3. A carton formed of two blanks of foldable material, one scored to provide a plurality of rectangular panels for forming the front, bottom, rear and top of the carton and the other blank being scored to provide the sides and inner bottom of the carton, all of said panels having tabs along certain of their edges adapted to be folded at right angles to the respective panels for reinforcing the corners of the carton, tongues formed on the free edge of the front and side forming panels of the carton and adapted to interlock with the tabs on the top forming panels, a binder about the top of the carton engaging the sides and top thereof, said front side having a door panel cut therefrom and adapted to be swung outwardly to permit access to the interior of the carton.

In testimony whereof I affix my signature.
THURE E. FLOOD.
